UNITED STATES PATENT OFFICE.

BERT McCARTY, OF TAMPA, FLORIDA.

HYDROCHEMICAL CLEANER.

1,421,971.

Specification of Letters Patent. Patented July 4, 1922.

Application filed November 1, 1920. Serial No. 421,145.

To all whom it may concern:

Be it known that I, BERT McCARTY, a citizen of the United States, and a resident of Tampa, in the county of Hillsborough and 5 State of Florida, have invented certain new and useful Improvements in Hydrochemical Cleaners, of which the following is a specification.

This invention relates to cleaning devices 10 and is especially adapted for use in cleaning jewelry and other small articles.

Particularly, this invention aims to provide simple means whereby jewelry and other small and precious articles to be 15 cleaned may be subjected to a uniform flow of cleaning liquid in such a manner that the liquid will be caused to thoroughly remove all particles of dirt from the article.

A further object of this invention is to 20 provide a cleaning device of the class described having simple means whereby the same may be conveniently assembled or prepared for operation.

The invention forming the subject matter 25 of this application aims also to provide a cleaning device for jewelry and other small articles which is simple to operate, efficient in use and cheap to manufacture.

Other objects and advantages of the invention 30 will be apparent during the course of the following description.

In the accompanying drawing forming a part of this application and in which like numerals are employed to designate like 35 parts throughout the same,

Figure 1 is a side elevation of the improved cleaning device,

Figure 2 is a central vertical longitudinal sectional view through the same,

Figure 3 is a horizontal sectional view 40 taken on line 3—3 of Figure 2, and

Figure 4 is a horizontal sectional view taken on line 4—4 of Figure 2.

In the drawings, wherein for the purpose 45 of illustration is shown a preferred embodiment of the invention, the numeral 5 generally designates a pump which principally consists of the usual cylinder 6 within which a piston 7 is slidably arranged. As illus-

trated in Figure 2, the piston which may be 50 of any desired construction is connected to a plunger 8 by means of nuts 10, and is adapted to reciprocate for drawing liquid into and discharging the same from the 55 cylinder. A closure 12 is arranged at the rear end portions of the cylinder 6 and is

provided with an annular attaching flange having oppositely arranged slots 14 adapted for the reception of locking lugs 16 carried by the upper or rear portion of the cylinder. 60 The closure 12 is also provided with several small apertures 16 by means of which air may be supplied to the cylinder 6 rearwardly of the piston 7 as the piston moves forwardly, and by means of which air may be 65 discharged from the cylinder as the plunger is drawn rearwardly.

As illustrated in Figures 1 and 2 the forward end portion of the cylinder 6 is provided with an annular attaching flange 18, 70 to which an article receiving receptacle generally designated by the numeral 20 is adapted to be detachably connected.

The article receiving receptacle 20 comprises spaced annuli 22 and 24 which are 75 connected by means of spacing strips 26. The spaced annuli 22 and 24 and the spacing strips 26 constitute the frame of the receptacle and a screening 28 constitutes the side walls of the receptacle. The screening 28 80 which is arranged in annular formation is soldered or otherwise secured to the inner side of the frame. The bottom wall of the receptacle 20 comprises attaching rims 30 and a screen 32 which is secured to the rim 85 by soldering or any other suitable means.

In attaching the receptacle 20 to the attaching flange 18, it is merely necessary to insert the oppositely directed lugs 34 carried by the annulus 22 into a pair of oppositely arranged bayonet slots 36 in the attaching flange 18. By giving the receptacle 20 a slight rotary motion the lugs 34 will be caused to enter the inner branches of the bayonet slots 36 whereby the receptacle will 95 be securely though detachably connected to the cylinder.

When preparing the device for use, rings or other small articles may be placed within the receptacle 20 which is foraminous, and 100 the receptacle may subsequently be connected to the attaching flange by inserting the radially extending pins 34 into the bayonet slots. The foraminous receptacle 20 may now be submerged within a quantity of 105 cleaning liquid and by giving the piston a rearward movement the liquid will be drawn through the foraminous receptacle into the cylinder. The liquid will of course be caused to flow directly into the receptacle and over 110 the articles of jewelry with the result that the rings or other small articles will be thor-

oughly cleaned. The outward movement of the piston will cause the liquid to flow freely about the rings. By reciprocating the piston slowly or rapidly as the occasion requires 5 the velocity of the liquid may be regulated. The rings or other small articles are prevented from entering the cylinder 6 by means of a screen 38 secured within the forward portion of the cylinder by means of a 10 two part retaining rim 40. When the foraminous receptacle 20 is attached to the pump the forward end of the cylinder 6 contacts with the adjacent edge of the annulus 22 so that the foraminous receptacle 15 will be held against movement by the radially extending lugs 34.

With reference to the foregoing description taken in connection with the drawings it will be observed that the cleaning device 20 constructed in accordance with this invention may be conveniently operated for thoroughly cleaning such small articles as jewelry. By the use of the device the operator need not submerge his hands in the cleaning 25 liquid and possibly cause himself injury.

Having thus described the invention, what is claimed is:

1. A portable cleaning device comprising a hand pump having a cylinder and a plunger, a cylindrical foraminous receptacle having an open end flatly abutting the forward end of said cylinder, said cylinder and said receptacle being of the same diameter, and an attaching flange surrounding the adjacent portions of said receptacle and said cylinder.

2. A portable cleaning device comprising a hand pump having a cylinder and a plunger, a cylindrical foraminous receptacle having an open end flatly abutting the forward end of said cylinder, said cylinder and said receptacle being of the same diameter, an attaching flange surrounding the adjacent portions of said receptacle and said cylinder, 45 the forward portion of said cylinder being provided with a reticulated end wall.

3. A portable cleaning device comprising a hand pump having a cylinder and a plunger, a cylindrical foraminous receptacle having an open end flatly abutting the forward end of said cylinder, and an attaching flange receiving the adjacent portions of said receptacle and said cylinder and having means for connecting the receptacle to the cylinder.

55 4. In a cleaning device, the combination

with a pump having a cylinder, provided with a stationary reticulated end wall, of an attaching member connected to the forward end of the said cylinder, and a foraminous receptacle having one end open and detachably connected to said attaching member.

5. The combination with a pump, of an attaching flange secured to the forward end of the same, the forward end of said pump being open, and a foraminous receptacle 65 having its rear end portion detachably received within said flange, the rear end of said foraminous receptacle being flatly engaged with the forward end of said pump, there being a pin and slot connection between said flange and said receptacle.

6. The combination with a pump, of an attaching flange secured to the forward end of the same, the forward end of said pump being open; a foraminous receptacle having 75 its rear end portion detachably received within said flange, the rear end portion of said foraminous receptacle being engaged with the forward open end of said pump, and pins carried by said receptacle and connected to said flange.

7. A cleaning device comprising a foraminous receptacle having spaced annuli and a foraminous portion, a flange adapted to detachably receive one of said annuli, said 85 flange being provided with locking slots, radially extending pins carried by said annuli and received within said slots, and means connected to said flange for directing a cleaning agent through the receptacle.

8. A cleaning device comprising a foraminous receptacle having an annulus and a foraminous portion, a flange adapted to detachably receive said annulus, said flange being provided with locking slots, radially 95 extending pins carried by said annulus and received within said slots, and means connected to said flange for passing a cleaning agent through said receptacle.

9. A cleaning device comprising a receptacle including spaced rims and strips connecting the rims, said receptacle being provided with foraminous walls secured to said rims and said connecting strips, an attaching member connected to one of said rims, and means connected to said attaching member for directing a cleaning agent back and forth through said receptacle.

BERT McCARTY.
